UNITED STATES PATENT OFFICE.

JOHN J. HILL, OF TONOPAH, NEVADA.

UNIVERSAL JIG.

1,244,210.

Specification of Letters Patent. Patented Oct. 23, 1917.

Application filed August 23, 1916. Serial No. 116,496.

To all whom it may concern:

Be it known that I, JOHN J. HILL, a citizen of the United States, residing at Tonopah, in the county of Nye and State of Nevada, have invented certain useful Improvements in Universal Jigs, of which the following is a specification, reference being had therein to the accompanying drawing.

This invention relates to improvements in universal jigs, one object of the invention being the provision of a jig which employs hydraulic and hydrostatic principles in concentrating ore and ore values and the removal of the lighter particles.

A further object of this invention is the provision of an apparatus in which hydraulic pressure in a confined receptacle is arranged so as to operate upon a movable body of ore to remove therefrom the lighter particles which are floated and the smaller heavier particles which are permitted to be precipitated, the main ore values being retained within the jig.

In the accompanying drawings:—

Figure 1 is a top plan view of a complete jig, made according to and embodying the present invention.

Fig. 2 is a longitudinal section taken on line 2—2 of Fig. 1.

Fig. 3 is a side elevation of the complete apparatus.

Fig. 4 is a cross section taken on line 4—4 of Fig. 1.

Figs. 5 and 6 are detail views of various parts.

Referring to the drawings, the numeral 10 designates the main reservoir or tank, which here shown, is provided in one side wall with the doors or closures 11 and the man hole 40 12, all of these being normally closed.

Disposed within the tank transversely thereof at proper intervals are static boards 13 which are supported in place by means of hinges 14.

Mounted horizontally within the tank and dividing the same into a lower compartment 15 and the upper compartment 16, is a partition 17 being provided with a plurality of openings 18 in which are set the open 50 frames 19, each of which constitutes a jig box.

In each box is mounted an auxiliary frame 20 carrying the screen bottom 21 reinforced by the transverse rods 22.

Mounted in the partition 17 and permitting communication between the two com-

partments, are the gage cocks 23 which also limit the water level above the partition 17 and also in the gage boxes.

A valved feed pipe 24 is connected in the partition 17 at one end so that water may be supplied to the compartment 15 and finally to the water level in the upper compartment 16, the passage of the water into the said upper compartment being permitted by the provision of the gage cocks 23 mounted in the partition 17. These gage cocks serve to maintain the proper water level at all times since it is to be appreciated that when ore is deposited in the jig boxes 70 it will to a certain extent form a substantial closure that would have a tendency to prevent an effective circulation of the water.

Formed in one end of the tank below the partition 17 are the discharge pipes 25 which are also valve controlled, so that the water therein may be retained or released, as desired.

At the opposite end of the tank below the partition 17 is an opening 26, in which is mounted the open ended cylinder 27 which constitutes with the plunger or piston 28, a pump, the cylinder 27 being in communication with the tank so that when the plunger 28 is reciprocated, the water within the tank 85 will be acted upon thereby.

Connected to the piston 28 is a piston rod 29 carrying the frame or tappet 30 disposed in the path of, to be engaged by, the cams 31 upon the driven shaft 32.

The piston rod 29 is mounted slidably in a boxing 33 and has mounted upon its extended end a coil spring 34 controlled by the adjusting member 35 which regulates the return stroke of the piston 28.

Thus, by rotating the shaft 32, the cams engage the tappet 30 and move the piston 28 inwardly, while the spring 34 moves the same outwardly.

This construction of pump is indicative of any form that may be used effectively in conjunction with the present invention.

Assuming that the chamber 15 is empty, and it is desired to use the present apparatus, the outlet or discharge pipes 25 are 105 closed, and the valve in the feed pipe 24 is opened, the gage cocks 23 also being opened.

When the water has filled the compartment 16 and assumes the water level indicated by the dotted lines in the jig boxes, 110 and above the partition 17, all water being released from below the partition, the feed

pipe is closed, and then the gage cocks are closed.

The shaft 32 is now operated to impart reciprocating movement to the piston 28 so as to cause an agitation of the water within the compartment 18 so that an up and down flow thereof is caused within the jig boxes.

The jig boxes are now filled with the ore to a point slightly below the water line. 10 Every inward thrust of the piston 28 will then force the water up through the ore in the jig boxes, causing the lighter particles or gangue to be floated to the surface or top, and precipitating the heavier particles upon 15 the screen 21 and permitting the finer particles to pass through the screen and be precipitated upon the bottom of the compartment, the return stroke of the piston assisting in directing the finer particles through 20 the screen and into the compartment, as aforesaid.

The lighter particles or gangue in the jig boxes are now removed with a square mouth shovel as waste, the heavier concentrates remaining upon the screen. 25

The jig boxes are again filled with the ore, and this operation is continued until all of said boxes are approximately one half full of the concentrates.

30 At this point, all concentrates are removed from all of the jig boxes and placed in bins by themselves, the boxes being again filled with the ore, and this operation continued repeatedly.

35 The compartment 15 does not have to be cleaned until the accumulation equals a predetermined amount, the finer and heavier particles being held in a static condition by means of the boards 14 and the action of the agitated water thereabove.

40 When sufficient finer particles have accumulated and it is desired to empty the compartment 15, the discharge pipes 25 are opened and the water drained.

45 Access to the bottom is then to be had through the doors 11, and also through the man holes 12, when desired.

By means of the adjustable tappet 30 and the spring 34, varying lengths of stroke may 50 be imparted to the piston 28, according to the weight of the ore treated.

In operation the piston is reciprocated approximately from sixty to one hundred strokes per minute, and as shown, the shaft 55 32 may be provided with loose and fast pulleys for belt driven, or in fact, with any other mechanism by means of which the same may be rotated and controlled.

60 In localities where water is a problem, that drained from the compartment 15 by the valves 25 may be saved and used again, the uppermost valves 25 being opened first, and so on, until all of the same are opened and the full amount of water discharged, 65 the gage cocks 23 having been previously

opened to permit of the easy flow of the water.

It will be pointed out that the spring 34 is adapted for storing energy from the motive power so as to operate upon the 70 piston rod 23 and its piston 28.

When the cams 31 act upon the tappet 30 the said spring 34 is tensioned, when the cams 31 ride off the tappet 30, and the said cams release the tappet, the spring becomes active to move the piston 28 outwardly from the cylinder 27, thereby giving a rapid action to the piston for creating sudden suction within the jig box, which serves to precipitate the heavier particles of mineral 75 through the screens into the tank bottom, so that in this manner the heavy slimes and heavier particles will be drawn through the screens to be delivered in the tank bottom, as will be clearly apparent. 80

85 What I claim as new is:—

1. In a universal jig, the combination of a tank, a horizontal partition extending throughout the length of the tank adjacent the upper edge and dividing the tank into 90 upper and lower compartments and having a plurality of openings therein, jig boxes supported in the openings having perforated bottoms, a plurality of static boards hinged at one of their ends to one of the sides of 95 the tank in the lower compartment and also arranged in close relation with the bottom, a plurality of gage cocks mounted in the partition establishing communication between the upper and lower compartments, 100 water inlet and outlet means in the tank, means in communication with one end of the lower compartment for agitating the water therein for affecting the ore and jig boxes, and a plurality of doors permitting 105 of access to the lower compartment adjacent the bottom.

2. In a universal jig, the combination of a tank, a horizontal partition extending throughout the length of the tank adjacent 110 the upper edge thereof and dividing the tank into upper and lower compartments and having a plurality of openings therein, jig boxes supported in the openings and having perforated bottoms, a plurality of 115 transversely arranged static boards in the lower compartment and adjacent the bottom thereof, a plurality of gage cocks mounted in the partition and establishing communication between the upper and lower compartments, a valve controlled inlet pipe mounted in the partition and communicating with the lower compartment, a series of superposed valve controlled outlet pipes adjacent one end of the tank, and 125 means in communication with the opposite end of the lower compartment of the tank for agitating the water therein for affecting the ore in the jig boxes.

3. In a universal jig, the combination of 130

- a tank, a horizontal partition therein adjacent the upper edge thereof for dividing the tank into upper and lower compartments and having a plurality of openings therein,
5   jig boxes embodying main frames supported in the openings, auxiliary frames arranged within the main frames, a piece of screen carried by each auxiliary frame and transverse rods carried by the auxiliary frame
10   for bracing the screens, a plurality of static boards having one of their ends hinged to one side of the tank and normally disposed transversely of and in close relation with the bottom of the tank, a plurality of gage
15   cocks mounted in the partition and establishing communication between the com-

partments, a valve controlled inlet pipe mounted in the partition and communicating with the lower compartment, a series of superposed valve controlled outlet pipes 20 mounted in one end of the tank and establishing communication with the lower compartment, means in communication with the opposite end of the lower compartment of the tank for agitating the water therein for 25 affecting the ore in the jig boxes, a plurality of doors mounted in one side of the tank adjacent the bottom thereof for permitting of access thereto, and a removable closed man hole in the tank. 30

In testimony whereof I affix my signature.
JOHN J. HILL.
